CONVECTOR CORE HANGER

Paul E. Brinen, Racine, Wis., assignor to Young
Radiator, Racine, Wis., a corporation of Wis-
consin

Application January 13, 1949, Serial No. 70,636

4 Claims. (Cl. 248—223)

1

The main objects of this invention are, to provide an improved form of convector-cabinet and heat-exchange-core assembly; to provide an improved form of suspension means for adjustably positioning the heat-exchange-core in the cabinet; to provide an improved core-suspension means which makes it very easy to place the core in or remove it from the cabinet and pitch the core at the most desirable angle to the horizontal; to provide an improved core-suspension means of this kind accommodated to the size of the core and affording a multiple-point suspension of said core at each end of the cabinet; to provide an improved core-suspension means of this kind which effects a locking of the core in place when the two-piece cabinet is assembled; and to provide an improved core-suspension means of this kind which is extremely simple and inexpensive to manufacture.

In the accompanying drawings:

Fig. 1 is a perspective view (partially broken away) of one type of cabinet and heat-exchange-core wherewith a suspension means constructed in accordance with this invention is particularly adapted for use.

Fig. 2 is a transverse sectional view of the same taken on the line 2—2 of Fig. 1.

Fig. 3 is a front elevation of the same, a part of the cabinet being broken away to more clearly show the suspended heat-exchange-core.

Fig. 4 is an enlarged fragmentary detail, partly in section, of the heat-exchange-core and the attached suspension plates by which the core is positioned on the cabinet.

Figs. 5, 6, 7, and 8 are perspective views of various sizes of suspension plates which are secured to the convector cabinet, the views showing the plates designed for 1-, 2-, 3-, and 4-point suspension, respectively.

Figs. 9, 10, 11, and 12 are perspective views of various sizes of suspension plates which are secured at each end of the core, the plates being formed to correspond with the 1-, 2-, 3-, and 4-point suspension form of the cabinet plates, respectively.

A convector, wherewith an improved suspension means embodying this invention is adapted for use, comprises a cabinet 14 and a heat-exchange-core 15 which are assembled with the core at the desired pitched relationship by the suspension means 16 whereof the herein-illustrated form is preferred.

The form of the cabinet 14 depends upon whether the convector unit is designed to be fully-recessed, partly-recessed, or fully-exposed.

2

The herein shown cabinet 14 is for a fully-exposed convector unit. Accordingly, the cabinet is formed with a main or exposed section 17 which is removably supported on a back 18.

5 The main or exposed section 17 is a sheet metal stamping formed with end flanges 19 adapted to fit over the end flanges 19' on the back 18 and with an inclined top 20. The top 20 has portions thereof cut and depressed to form a grill 10 21. The movement of air through said grill is controlled by a damper 22 hingedly suspended from the underside of the top 20 and angularly positioned by a chain 23.

The back 18 is likewise a sheet metal stamping 15 formed with end flanges 19' adapted to fit within the front end flanges 19, as most clearly indicated in Fig. 2. Angularly-disposed notches 19a (see Fig. 2) in the forward edges of the flanges 19' near the bottom thereof receive pins 19b on the 20 front flanges 19 and coat with screws 19c (see Fig. 1) to secure the front 17 in proper position on the back 18.

The heat-exchange-core 15 is of a more or less conventional construction comprising a pair of 25 headers 24 between which extend two or more rows of tubes 25 and on which are assembled a plurality of fins 26.

The headers 24 are generally castings with transversely-disposed parts somewhat in the 30 form of a cross. One of the parts of each is provided with parts 27 one of which, in an assembled core 15, serves as a heating fluid inlet and the other as an outlet.

The tubes 25, of which there are generally two 35 or more, up to five or six, have their ends extending through the headers 24 and are anchored thereto in a suitable manner. Similarly, the fins 26 are of a conventional form and are secured in closely spaced relationship on each of the tubes 40 25. Side plates 26' are locked over the edges of the fins 26. Incidentally, the distance between the side plates 26' is such that the core 15 fits snugly between the assembled front 17 and back 18, as indicated in Fig. 2.

45 The preferred form of means herein shown for suspending a heat-exchange-core 15 in a cabinet 14 comprises pairs of plates 29 and 30. The former pair is designed for attachment to the cabinet 14; the latter pair for attachment to the heat-exchange-core 15. Lugs 31 on the plates 29 are admitted through openings 32 into the slots 33 to rest on the fingers 34 whereby the heat-exchange-core 15 is positioned in proper 50 pitched relationship in the cabinet 14.

55 The plate 29 is a flat strip of metal with one

or more vertically-arranged pairs of lugs 31 punched out from the strip and upwardly disposed in parallel relationship with the plate. As shown in Fig. 5 there may be one pair of vertically-arranged lugs 31 or, as shown in Figs. 6, 7, and 8, there may be a plurality of vertically-arranged pairs of lugs 31, depending upon the size of the core 15. The plate 29 is generally spot-welded on the inner face of the cabinet ends 19, a predetermined distance above the bottom edge thereof.

Each plate 30 is formed to simulate a chair with sections 35 and 36 disposed parallel in opposite directions from a transverse part 37. The section 35 is punched with two or more circular openings 38 for receiving the heating core tubes 25, whereas the section 36 is formed with one or more of the elongated openings 32 for receiving the lugs 31.

The size of a plate 30 depends upon the size of the heat-exchange-core 15 wherewith it is to be used to support a core 15 within a cabinet 14. Accordingly, the sections 35 of the plates 30 are made of a width to permit the formation of as many openings 38 as there are tubes 25 in the heat-exchange-unit 15 that is to be supported by a particular pair of plates 30. The section 36 is narrower than the corresponding section 35, there being one less opening 32 in the section 36 than there are openings 36 in the section 35.

The openings 32 extend vertically of a section 36 and are of a width but slightly greater than the transverse width of the lugs 31. This permits the lugs 31 to be received in the openings 32 and allows a free vertical relative movement of the plates 29 and 30. The slots 33, extending transversely of the main part of the openings 32 on the opposite sides thereof, are of a height to accommodate the lugs 31 and permit them to rest on the fingers or ledges 34 whereby the heat-exchange-core 15 is suspended from the cabinet 14. The depth of the slots 33 is such that when the lugs 31 are fully seated therein the side plates 26' of the core unit 15 will abut the assembled cabinet front 17 and back 18. There being a plurality of these slots 33, the heat-exchange-core 15 may be supported at any desired pitch (see Fig. 3) within the limits of the length of the main openings 32 on opposite plates 30.

With this form of hanger construction, and with a core unit 15 of a width between side plates 26' to exactly fit between the assembled cabinet front 17 and back 18, the core unit 15 is locked in the pitched position where set and can be changed only after first removing the cabinet front 17.

Variations and modifications in the details of structure and arrangement of the parts may be resorted to within the spirit and coverage of the appended claims.

I claim:

1. A hanger for suspending one object on another comprising, a pair of plates respectively attachable to the two objects, one of the plates 65 having one or more lugs formed therein disposed outwardly from the face of the plate, the other plate having one or more vertical elongated openings formed therein with a plurality of transverse slots communicating with the respective openings to form a plurality of lug-supporting ledges normal to the length of the opening and each ledge dimensioned to engage and retain a lug thereon whereby the other object is adjustably supported on the one object.

2. A hanger for suspending one object on another comprising, a pair of plates respectively attachable to the two objects, one of the plates having one or more lugs formed therein disposed outwardly from the face of the plate, the other plate having one or more vertical elongated openings formed therein with a plurality of transverse slots on opposite sides of and communicating with the respective openings to form a plurality of opposed lug-supporting ledges normal to the length of the opening and each ledge dimensioned to engage and retain a lug thereon whereby the other object is adjustably supported on the one object.

3. A convactor heat-exchange core hanger comprising, pairs of plates one pair of which is attachable to a convactor cabinet and the other pair of which is attachable to a heat exchange core, each of the one pair of plates having a plurality of lugs arranged thereon in transverse rows, each of the other pair of plates being shaped with a pair of parallel sections extending in opposite directions from a transverse intermediate part one of which sections is formed with openings to fit over the tubes of a heat-exchange core, the other plate section of each pair having formed therein vertical elongated openings one for each row of lugs with a plurality of transverse slots on each side of the respective openings and communicating therewith to form opposed horizontally-supporting ledges normal to the respective openings and each ledge of a dimension not less than half the width of one of the lugs.

4. A hanger for suspending from the inside of a convactor cabinet a heat-exchange core of the type embodying a plurality of tubes spanning and connected to spaced headers, the hanger comprising, pairs of plates one pair of which is adapted for attachment to the cabinet walls and each having one less vertical row of lugs than there are tubes extending between the headers, the other pair of plates each being shaped with a pair of parallel sections extending in opposite directions from a transverse intermediate part, one section of each of the other pair of plates having openings formed therein to fit over the respective core tubes inwardly of the headers for supporting the core on the pair of plates, the other plate section having formed therein a vertical elongated opening for each of the row of lugs with a plurality of transverse slots on each side of the respective plate opening and communicating therewith to form opposed horizontal ledges normal to the length of the respective opening and each ledge of a dimension not less than half the width of one of the lugs.

PAUL F. BRINEN.
